UNITED STATES PATENT OFFICE.

PER UTNE, OF EDGEWOOD PARK, PENNSYLVANIA, ASSIGNOR TO THE UNION SWITCH & SIGNAL COMPANY, OF SWISSVALE, PENNSYLVANIA, A CORPORATION OF PENNSYLVANIA.

APPARATUS FOR THE CONTROL OF RAILWAY CARS OR TRAINS.

1,110,412.

Specification of Letters Patent. Patented Sept. 15, 1914.

Application filed September 7, 1911. Serial No. 648,116.

To all whom it may concern:

Be it known that I, PER UTNE, a subject of the King of Norway, and residing at Edgewood Park, in the county of Allegheny and State of Pennsylvania, United States of America, have invented certain new and useful Improvements in Apparatus for the Control of Railway Cars or Trains, of which the following is a specification.

My invention relates to apparatus for the control of brakes for railway cars or vehicles, and particularly to apparatus for automatically applying the brakes of a car or train when such car or train passes a point at which it should stop, such as when it passes a signal set at danger.

I will describe one form and arrangement of apparatus embodying my invention, and then point out the novel features thereof in claims.

In the accompanying drawings, Figure 1 is a diagrammatic view showing one form and arrangement of apparatus embodying my invention. Figs. 2, 3 and 4 are respectively a longitudinal vertical sectional view, a horizontal sectional view, and an end elevation, partly sectional, showing in detail the tripping device carried by a car and illustrated diagrammatically in Fig. 1. Figs. 5 and 6 are respectively vertical sectional views showing in detail the electro-magnetically controlled exhaust valve, and the pressure controlled circuit controller, illustrated in outline in Fig. 1.

Similar reference characters refer to similar parts in each of the several views.

Referring first to Fig. 1, I will mention the essential parts of the system therein illustrated, and will then describe certain of these parts in detail referring to the succeeding views. 10 designates a railway car or train, and 11 a portion of a "train pipe" carried by the car or train. It is understood that the car or train is equipped with a braking system of any of the usual types. I have illustrated my invention in connection with a fluid pressure braking system in which the brakes are held released when the fluid pressure (usually compressed air) in the train pipe is at or above a predetermined

point, and are applied when the air pressure in the train pipe falls below such predetermined point. The train pipe 11 is supplied with air pressure from a suitable source such as a pump or a reservoir, which source is not shown in the drawings. 13 designates a mechanism comprising an exhaust port for the train pipe, a fluid pressure device for the control of the exhaust port, and an electromagnet 16 for the control of the fluid pressure device, which mechanism is illustrated in detail in Fig. 5. 12 is a circuit controlling device for the control of the circuit of electromagnet 16, which circuit controlling device is adapted to be operated by the engagement of a trip arm 17 with a stop arm 15. It is understood that the stop arm 15 is located alongside the trackway and is moved into or out of position for engagement with the trip arm 17 whereby the car or train may be automatically stopped or may be permitted to proceed. As here shown, the circuit controlling device 12 is located adjacent the top of the car 10, and the stop arm is suspended above the trackway, although I do not wish to be limited to this specific location of these parts. The stop arm 15 may be operated by any suitable means (not shown herein). For example it may be operated by direct connection with a signal device, in which case the arrangement of connections would usually be such that when the signal device is in the clear or proceed position the stop arm 15 would be held out of position for engagement with trip arm 17, and when the signal device is in the danger or stop position the stop arm 15 would be held in position for engagement with the trip arm 17 whereby the circuit controller operated by the trip arm would be actuated to cause the exhaust port to open. The circuit controlling device 12 is illustrated in detail in Figs. 2, 3 and 4. 14 is a circuit controlling device controlled by a diaphragm which is responsive to variations of the air pressure in the train pipe 11; this circuit controlling device is illustrated in detail in Fig. 6. 20 designates an auxiliary reservoir which is connected with the train pipe through a check valve 21, which valve permits air to

flow from the train pipe to the reservoir but prevents flow of air in the reverse direction. The remaining parts of the apparatus shown in Fig. 1, and the circuits connecting the various parts, will be explained hereinafter in connection with the operation of the system.

Referring now to Fig. 5, the mechanism 13 comprises a cylinder 22 and a piston 23 movable therein. One end of the cylinder is connected with the train pipe through a pipe 19 (see also Fig. 1) and the same end of the cylinder is also open to atmosphere through an exhaust port 24. This same end of the cylinder is provided with an inwardly extending valve seat 25 with the end of which the piston 23 is adapted to engage. The piston is provided with a facing 26 of leather or of other similar material in order to tightly cover the valve seat 25 when the piston is in the extreme right hand position of its stroke. It will be clear that when the piston 23 is not in the extreme right hand position of its stroke the pipe 19 will be open to atmosphere through the port 24. 18 designates a pipe connected with the reservoir 20 (see Fig. 1). The left hand end of cylinder 22 is connected with either the pipe 18 or with atmosphere by means of a valve device 27. This valve device comprises two valves 28 and 29 which are rigidly connected and are moved to one position by means of a spring 30 and to another position against the action of this spring by a rod 32 which is connected with an armature 33 of electromagnet 16. The valve 29 opens and closes the passage between the pipe 18 and the cylinder 22, and the valve 28 opens and closes the passage between the cylinder 22 and atmosphere. It is understood that when valve 28 is seated, valve 29 is unseated, and vice versa. An electro-magnetically controlled valve device of this character is shown and described in United States Letters Patent No. 357,109 granted to George Westinghouse, Jr., on February 1, 1887.

It will be noted that when the piston 23 is in the extreme right hand position of its stroke, the area of the piston exposed to the fluid pressure in the left hand end of the cylinder is greater than the area exposed to the fluid pressure in the right hand end of the cylinder. Hence when the left hand end of the cylinder is connected with pipe 18 and the fluid pressure in pipes 18 and 19 is substantially equal the piston will be held in the extreme right hand position of its stroke and the exhaust port 24 is held closed; but when the left hand end of cylinder 22 is opened to atmosphere the pressure in pipe 19 will move the piston 23 to the left thereby opening the pipe 19 to atmosphere through exhaust port 24. The operation of this mechanism will be more fully explained hereinafter in connection with the operation of the entire system.

A spring 34 is preferably employed to hold piston 23 against the valve seat 25 when there is no fluid pressure on either side of the piston, this being the proper position of the piston to permit the pressure in the train pipe to be raised by the pumps or other means. 35 is a circuit controller operatively connected with armature 33, the contacts of which controller are closed when the magnet is energized and open when the magnet is de- 75 energized.

Referring to Fig. 6 it will be seen that the device 14 comprises a chamber 36 the lower portion of which is connected with the train pipe through a pipe 37 (see also Fig. 1). 80 This chamber contains a movable member which is responsive to variations of the pressure in the train pipe; as here shown this movable member is a flexible diaphragm 38, although I do not wish to be limited to this specific type of movable member. The diaphragm 38 is operatively connected by means of a rod 39 with a circuit controller 40. The parts are so adjusted that while the pressure in the train pipe is at or above a predetermined point the contacts of circuit controller 40 are held open; but when the pressure in the train pipe falls below the predetermined point the contacts of the circuit controller are closed. This adjustment will be referred to and more fully explained hereinafter. 95

Referring now to Figs. 2, 3 and 4 I will describe in detail the trip actuated circuit controlling device 12. As here shown the trip arm 17 is rigidly secured to a shaft 41 109 suitably journaled in two opposite sides of a box 42. 43, 43 designate two arms rotatably mounted on a pin 45 which is supported in a suitable lug 46 forming part of the box 42. Riveted to the arms 43 is a knob 47 of insulating material, which knob is adapted to engage with a circuit controlling finger 44 in such manner as to hold the contact closed when the arms are in their upper position and to permit the contact to open when the 110 arms are in their lower position. The arms 43 are normally held in their upper position by means of a spring 48. 49 designates a cam secured to the shaft 41, the face of which cam is adapted to engage with a roller 115 50 mounted between the arms 43. As is clearly shown in Fig. 2, when the trip arm 17 is in a substantially vertical position the cam 49 permits the arms 43 to be drawn to the upper extremity of their stroke by the 120 spring 48. When however the trip arm is rotated in the direction indicated by the arrow in Fig. 2, as by engagement with a stop arm, the face of the cam 49 coacts with the roller 50 to move the arms 43 downwardly 125 to their lower position against the action of spring 48. If desired, the cam 49 may be so constructed that when the trip arm is rotated in the direction opposite to that indicated by the arrow the arms 43 will be moved 130

downwardly in a similar manner. But as here shown the cam is so constructed that if the trip arm 17 should be rotated in the direction opposite to that indicated by the 5 arrow in Fig. 2, as for example by the engagement with a stop arm when the car or train is running in the direction opposite to normal traffic, the face of cam 49 would merely slide on roller 50 without any tendency to move the arms 43 downwardly. The trip arm 17 is held normally in the vertically upward position, and is returned to such normal position after being rocked in either direction, by means of a centering device 10 which I will now describe. 64 designates a plate secured to one end of the box 42, in which plate two pins 60 and 61 are mounted to project inwardly. These pins serve as guides for two centering springs 58 and 59. 62 designates a tube (see Fig. 3) adapted to slide freely inside of spring 58 and over pin 60. A similar tube slides in spring 59 but is not shown in the drawings. These tubes terminate in end pieces 54 and 25 55 the shapes of which are clearly indicated in Fig. 2. As will be seen in this view, each end piece is provided with an ear adapted to engage respectively with pins 56 and 57, which pins are suitably mounted in the box 30 42. The ears are normally held in engagement with these pins by the pressure of springs 58 and 59 on the enlarged end pieces of the tubes. A cam 51 rigidly secured to the shaft 41 is provided with two projecting 35 lugs 52 and 53, which lugs are adapted to engage respectively with extensions of the two end pieces 54 and 55 as clearly shown in Fig. 2. When the trip arm 17 is vertical the two lugs 52 and 53 are adjacent the two 40 extensions but no pressure is exerted upon the lugs because the end pieces are in engagement with the stationary pins 56 and 57. When however the trip arm 17, and therefore the shaft 41, is rotated in one direction 45 or the other from the normal vertical position, one or the other of the lugs 52 or 53 engages with the corresponding end piece 54 or 55, thereby compressing one of the springs 58 or 59. It is evident that as soon as the 50 outside force tending to rotate the trip arm is removed, the arm will be immediately returned to its vertical position by the action of the compressed spring.

After the arms 43 have been moved downwardly by the action of cam 49, it is desirable that their return movement under the action of spring 48 should be retarded thereby holding the contact of circuit controller 44 open for a short period of time. As here shown I obtain the retardation by means of a buffering device which I will now describe. 66 designates a cylinder which is suitably mounted upon lugs adjacent one corner of the box 42. This cylinder is closed at the 60 top and open at the bottom, and is provided

with a piston 67 which is operatively connected with the arms 43 and which fits loosely in the cylinder to permit the slow escape of air from above the piston during the upward movement of the piston. The 70 piston 67 is provided with a valve 69 so arranged that when the piston is moved in a downward direction the valve will allow air to pass freely through holes 68 into the space above the piston; but when the piston is moved upwardly the holes 68 are closed by gravity and by the pressure upon the valve of the air above the piston, hence the speed of the upward movement of the piston is retarded by the compression of the air 75 above the piston. As here shown, this valve 80 69 comprises a disk having movement relatively to the piston.

Referring now to Fig. 1, I will explain the operation of the entire apparatus therein 85 illustrated. When the fluid pressure in the train pipe is normal and the trip arm 17 is vertical, a circuit through electro magnet 16 is closed as follows,—from battery 70 through wire 71, magnet 16, wire 72, circuit controller 35, wire 73, circuit controller 44, wires 74, 75 and 78 to battery 70. Magnet 16 is thereby energized, holding valve device 27 (see Fig. 5) in such position that the left hand end of cylinder 22 is connected with 90 pipe 18. Piston 23 is therefore held at the right hand end of its stroke and the exhaust port 24 is closed. Circuit controller 40 is held open because the pressure on the diaphragm is above the point at which these 95 contacts close. It will be noted that the circuit just traced through magnet 16 passes through circuit controller 35 operated by the armature of this magnet, hence when the circuit through this magnet is once opened 100 it cannot again be closed until the contacts of circuit controller 40 are closed thereby forming a temporary shunt around circuit controller 35. Assume now that circuit controller 44 is opened by the engagement of 105 trip arm 17 with a stop arm 15. The contact will be held open during a short period of time by the buffering device, and this period of time is sufficient for magnet 16 to release its armature. The release of this armature 110 opens circuit controller 35, hence magnet 16 cannot be again energized until circuit controller 40 has been closed by the reduction of pressure in the train pipe. The release of armature 33 permits the valve device 27 115 120 to be reversed, thereby opening the left hand end of cylinder 22 to atmosphere (see Fig. 5) and disconnecting pipe 18 from this end of the cylinder. The fluid pressure on the right hand face of piston 23 will then move this 125 piston to the left, connecting the pipe 19 with atmosphere through the exhaust port 24. The fluid pressure in the train pipe will then be rapidly reduced and the brakes 130 therefore applied to stop the car or train.

- When the pressure in the train pipe has fallen below a predetermined point the diaphragm 38 (see Fig. 6) will permit circuit controller 40 to close, and a branch circuit 5 will then be closed through magnet 16 as follows,—from battery 70 through wire 71, magnet 16, wires 72 and 76, circuit controller 40, wires 77, 75 and 78 to battery 70. The magnet being then energized, its armature 33 is attracted, moving the valve device 27 to disconnect the left hand end of cylinder 22 from atmosphere and connect the cylinder with pipe 18. Since the fluid under pressure in the reservoir 20 and pipe 18 is 10 prevented by the check valve 21 from flowing back into the train pipe when the pressure in the train pipe is reduced, the pressure in pipe 18 remains high and will therefore move the piston 23 to the right, closing 15 exhaust port 24. The train pipe being then closed, its pressure may again be increased to the normal point by fluid pressure from the main source, during which increase the diaphragm 38 will be operated to open circuit controller 40; but circuit controller 35 is now closed hence the circuit through magnet 16 is the same as that first traced, and this circuit is ready to be again opened by 20 circuit controller 44.
- 30 It will be noted that in a control system embodying my invention, as soon as the brakes have been applied to stop the car or train the train pipe is again closed to permit the pressure to rise and to thereby release 35 the brakes; hence after the car or train is brought to a stop no attention is required on the part of the train crew to place the brakes in condition to proceed.
- Although I have shown a reservoir 20 and 40 a check valve 21 between the train pipe and the valve device 27, these parts are not essential to the operation of the system, and may be dispensed with if desired. In such case the valve device 27 is connected directly 45 with the train pipe by means of the pipe 18, and the pressure remaining in the train pipe after an application of the brakes will be sufficient to move the piston to its right hand position when the left hand end of the cylinder 50 is connected with pipe 18. This movement of the piston is due to the fact that the pressure on the right hand face of the piston is lower than that on the left hand face because the right hand end of the cylinder 55 is directly open to atmosphere through the port 24. Or if the pressure in the train pipe is completely exhausted the piston will be moved to its right hand position by the action of spring 34.
- 60 In Fig. 1 I have shown my invention as applied to a car or train using electric propulsion current, but it is understood that it may equally well be applied to a car or train propelled in any manner. In the case

of direct propulsion current, however, as indicated in Fig. 1, the battery 70 may be of the storage type and may be connected in a branch around the motor circuit and in series with a suitable resistance 83. By means of this arrangement the battery will be kept 70 fully charged and will require the minimum amount of attention; in fact the magnet 16 will be energized by the propulsion current at all times except when such current is for any reason interrupted, and at such times 75 the battery 70 will supply current to the magnet.

Although I have herein shown and described only one form and arrangement of apparatus embodying my invention, I do 80 not wish to be limited to this particular form and arrangement, it being understood that various modifications may be made therein within the scope of the appended claims without departing from the spirit 85 and scope of my invention.

Having thus described my invention, what I claim is,—

1. In combination, a train pipe, means for opening said train pipe, an electromagnetic device for controlling said means, a circuit controller controlled by said electromagnetic device and operating after the device has become deenergized to keep it deenergized, and means responsive to the fluid pressure in said train pipe for rendering said circuit controller ineffective to control the electromagnetic device.

2. In combination, a train pipe, means for opening said pipe, an electromagnetic device for controlling said means, a circuit for said electromagnetic device, means for opening said circuit, a contact controlled by said device for keeping the circuit open after it has been opened, and means responsive to the fluid pressure in said train pipe for rendering said contact ineffective to control the circuit.

3. In combination, a train pipe, means for opening said train pipe, an electromagnetic device for controlling said means, a contact operatively connected with said device for controlling the device, and means responsive to the fluid pressure in said train pipe for rendering said contact ineffective to control 11 said electromagnetic device.

4. In combination, a train pipe, means for opening said pipe, a device controlled by said opening means for retaining said opening means in the opening position, and means responsive to the fluid pressure in the train pipe for rendering said device ineffective to control said opening means.

5. In an apparatus for the control of fluid pressure brakes, the combination of a 12 train pipe, an exhaust port in the train pipe, an electro-magnet for the control of the exhaust port, a circuit controller oper-

ated by the electro-magnet, a movable member connected with the train pipe and responsive to variations of pressure therein, a circuit controller operated by said member, 5 a circuit for the electro-magnet including a source of current and the circuit controller operated by the electro-magnet, means for controlling said circuit, and a branch circuit around the circuit controller operated 10 by the electro-magnet and including the circuit controller operated by the movable member.

6. In an apparatus for the control of fluid pressure brakes, the combination of a train pipe, an exhaust port in the train pipe, an 15 electro-magnet, means controlled by the electro-magnet for holding the exhaust port closed or open, a circuit controller operated by the electro-magnet and arranged to be 20 closed or open according to whether the magnet is energized or deenergized, a movable member connected with the train pipe and responsive to variations of pressure therein, a circuit controller operated by the 25 movable member and arranged to be open or closed according to whether the pressure in the train pipe is above or below a predetermined point, a circuit for the electro-magnet including a source of current and the circuit 30 controller operated by the electro-magnet, means for controlling the said circuit, and a branch circuit around the circuit controller operated by the electro-magnet which branch circuit includes the circuit controller operated 35 by the movable member.

7. In an apparatus for the control of fluid pressure brakes, the combination of a train pipe, an exhaust port in the train pipe, a fluid pressure device for the control of the 40 exhaust port, an electro-magnet for the control of the fluid pressure device, a circuit controller operated by the electro-magnet, a movable member connected with the train pipe and responsive to variations of pressure 45 therein, a circuit controller operated by the movable member, a third circuit controller which is normally closed, means for opening said third circuit controller, a circuit for the electro-magnet including a source of current, 50 the circuit controller operated by the electro-magnet and the third circuit controller; and a branch circuit around the circuit controller operated by the electro-magnet and including the circuit controller operated by the movable member.

8. In an apparatus for the control of fluid pressure brakes, the combination of a train pipe, an exhaust port in said train pipe, an electro-magnet for the control of the exhaust 55 port, a circuit controller operated by the electro-magnet, a movable member connected with the train pipe and responsive to variations of pressure therein, a circuit controller operated by said member, a third circuit con-

troller which is normally closed, means for 65 opening said third circuit controller; a circuit for the electromagnet including a source of current, the circuit controller operated by the electromagnet, and the third circuit controller; and a branch circuit around the electromagnet circuit controller, which branch circuit includes the circuit controller operated by the movable member. 70

9. In an apparatus for the control of fluid pressure brakes, the combination of a train pipe, an exhaust port in said train pipe, an electromagnet for the control of the exhaust port, a circuit controller operated by the electromagnet, a movable member connected with the train pipe and responsive to variations of pressure therein, a circuit controller operated by said member, a third circuit controller which is normally closed, means for opening said third circuit controller, means for retarding the closing of said last-mentioned circuit controller after it has been opened; a circuit for the electromagnet including a source of current, the circuit controller operated by the electromagnet and the third circuit controller; and a branch circuit around the electromagnet circuit controller which branch circuit includes the circuit controller operated by the movable member. 80

10. In an apparatus for the control of fluid pressure brakes, the combination of a train pipe, an exhaust port in the train pipe, a fluid pressure device for the control of the exhaust port, a valve for the control of the fluid pressure device, an electromagnet operatively connected with the valve, a circuit controller operated by the electromagnet and arranged to be closed or open according to whether or not the electromagnet is energized, a movable member connected with the train pipe, a circuit controller operated by the member and arranged to be closed or open according to whether the pressure in the train pipe is below or above a predetermined point, a third circuit controller which is normally closed, means for opening said third circuit controller; a circuit for the electromagnet including a source of current, the circuit controller operated by the electromagnet and the third circuit controller; and a branch circuit around the two last-mentioned circuit controllers and including the circuit controller operated by the movable member. 105

11. In combination, a train pipe, a cylinder, a differential piston movable therein, means for connecting the train pipe with the end of the cylinder exposed to the smaller face of the piston, a reservoir connected with the train pipe, a check valve interposed between the reservoir and the train pipe for preventing the flow of fluid from the reservoir to the train pipe; a valve device adapt- 110 120 125

ed when in one position to connect the other end of the cylinder with the said reservoir, and when in another position to disconnect the cylinder from the reservoir and to connect the cylinder with atmosphere; and means controlled by said piston for opening and closing the train pipe.

In testimony whereof, I affix my signature in presence of two witnesses.

PER UTNE.
